CONNECTOR DEVICE

Joseph W. Turner, Sr., Rte. 1, Box 53, Bandon, Oreg.
Filed Aug. 7, 1964, Ser. No. 388,234
5 Claims. (Cl. 294—78)

The instant invention pertains to connector devices and, more specifically, connector devices that are adapted for connection with the cables of derricks, hoists, and other similar lifting mechanisms.

One of the primary objects of this invention is to provide an improvement in connecting devices which particularly lend themselves to the hoisting of timber, lumber, steel beams, and other objects which must necessarily be elevated from one given position and lowered to a desired site.

Another object of this invention is to provide a connector device which readily adapts itself to connection to one or more objects around which has been passed a connector chain, the connector device being readily adaptable for connection with the chain and connected with a hoisting device whereby the object to be moved may be readily transported to the desired site.

Still another object of this invention is to provide a connector device of the type generally described above, the device being formed in two parts and including positive locking means for insuring against accidental or inadvertent separation of the parts as the lifting operation is being carried out.

Still another object of this invention is to provide a connector device of the type generally referred to supra, wherein the separable parts of the lifting device may be quickly and easily assembled in their locking condition and wherein the same may, with the same facility, be disassembled after the work has been transported to the desired site.

This invention contemplates, as a still further object thereof, the provision of a connector device of the type generally described above, wherein the device is non-complex in construction and assembly, inexpensive to manufacture and maintain, and which is durable in use.

Other and further objects and advantages of the instant invention will become more manifest from a consideration of the following specification when read in conjunction with the annexed drawing, in which:

FIGURE 1 is a side elevational view of the two halves of a connector device constructed in accordance with this invention;

FIGURE 2 is a perspective view of the two halves of the connector device shown in FIGURE 1;

FIGURE 3 is a side elevational view of the two halves of the connector unit in their respective interlocking, but non-operative positions;

FIGURE 4 is a side elevational view of the two halves of the connector device in their respective operative positions and illustrating the same supporting a load;

FIGURE 5 is an enlarged detail, cross-sectional view, FIGURE 5 being taken substantially on the vertical plane of line 5—5 of FIGURE 3, looking in the direction of the arrows; and

FIGURE 6 is an enlarged detail, cross-sectional view, FIGURE 6 being taken substantially on the line 6—6 of FIGURE 4, looking in the direction of the arrows.

Reference numeral 10 designates, in general, a connector device constructed in accordance with the teachings of this invention. The connector device 10 is seen to comprise a pair of complementing male and female connector elements 12, 14, respectively (see FIGURES 1 and 2), which are essentially arcuately-shaped in side elevation and each of the connector elements 12, 14 is provided with one arm 16, 18, respectively, which is somewhat longer than

2

the opposing arms 20, 22 of the connector elements 12, 14, respectively. The outer ends of the arms 16, 18 are provided with transversely-extending openings 24, 26, respectively, to serve a function to be described.

- 5 The arcuate male connector element 12 is seen to include a substantially planar inner surface 28 and rising therefrom in inwardly-spaced relation relative to the bight portion 30 is an arcuate flange 32. The flange 32, adjacent the central portion thereof, is integral with a modified dovetailed key 34 (see FIGURES 5 and 6) which extends therefrom and has an angularly-inclined undercut outer side 36.
- 10 The female connector element 14 is also provided with a substantially planar inner surface 38 which is formed with an inwardly-extending substantially arcuate groove 40 that gives rise to an arcuate shoulder 42 adjacent the bight portion 44 thereof. Formation of the groove 40 inherently forms an outer peripheral arcuate shoulder 46 disposed in laterally-spaced and substantially concentric relation with respect to the shoulder 42. The shoulder 46 is formed with a centrally-disposed offset arcuate recessed segment 48 having a curvilinear surface corresponding to the curvilinear surface of the dovetailed key 34, and the shoulder 46 at each terminal end of the recessed segment 48 continues into an undercut 50 formed in the shoulder 46.
- 15
- 20
- 25

It should be here noted that one end 32' of the flange 32 is coplanar with the inner side of the arm 16 and its other terminal end 32" is coplanar with the outer end 30 of the arm 16. In a similar manner, one end of the groove 40 opens into the inner side of the arm 18, while its other end opens in the terminal end of the arm 22.

To assemble the connector elements 12, 14, the planar surfaces of the male and female connector elements 12, 14 are brought into face-to-face contact in such a manner as to cause the key 34 to enter the recessed segment 48 and with the flange 32 engaging within the groove 40. It will now be recognized that a slight turn of one or the other of the connector elements 12, 14 in such direction as to turn the arms 16, 18 toward one another (see FIGURES 3 and 4) will cause the key 34 to lock in the groove 40 to prevent separation of the male and female connector elements 12, 14, respectively, as is shown clearly in FIGURE 6 of the drawing.

45 In FIGURES 1 to 4, inclusive, the male and female connectors 12, 14 are shown as having the terminal ends of a flexible cable 42 threaded through the openings 24, 26. The threaded ends are reverted and spliced back, or otherwise secured to the cable 42, as at 44. In use, it is desirable that the bight portion 46 of the cable 42 be carefully located intermediate the ends of the cable 42 in order to receive a hook 52 of a hoisting device (not shown) therethrough.

FIGURE 3 shows the connector device 10 with the male and female connector elements 12, 14 in their respective open positions and with the cable 42 in its slack-off condition. In the open positions shown in FIGURE 3, the key 34 rides, of course, within the undercut 50 to securely hold the male and female connectors 12, 14 in locking engagement, one with the other. A hook 52 may now be engaged over the bights 30, 44, after which the hoisting device is operated to remove the slack from cable 42 which, of course, causes the arms 16, 18 to move toward each other and to assume their locked position, as shown in FIGURE 4. As the cable 42 continues to be placed under tension and rises, the hook 52 will move therewith and will lift any load (not shown) which may be connected with the hook 50.

70 It will be readily appreciated that, in place of the hook 52, a closed loop (not shown) may surround to load to be moved, and in this case, and assuming there is

a certain amount of slack in the loop, the male and female elements 12, 14 could be separated and passed under the loop in opposite directions after which the male and female elements 12, 14 could be rejoined in the manner described above.

Having described and illustrated one embodiment of this invention in detail, it will be understood that the same is offered merely by way of example, and that this invention is to be limited only by the scope of the appended claims.

What is claimed is:

1. A connector device comprising arcuately-shaped male and female connector elements each having planar surfaces adapted for surface-to-surface contact, said male element having a dovetailed flange projecting laterally therefrom, said female element having an undercut slot extending inwardly from said surface, and said groove including an offset recess to initially receive said dovetailed flange therein, said flange and groove being interlocked by turning one of said elements relative to the other.

2. A connector device comprising an arcuately-shaped pair of male and female connector elements, respectively, each of said connectors having one arm thereof longer than its opposed arm, means on each of said longer arms 25 for connection with a hoisting cable, each of said connector elements having planar surfaces adapted for surface-to-surface contact, said male connector element having a substantially arcuately-shaped flange projecting laterally from said planar surface, said flange having a centrally-located dovetailed key projecting laterally from the bight portion thereof, said female connector element

5 having a groove formed therein adapted to receive said flange, said groove having a centrally-located recess offset therefrom to receive said dovetailed key, said male and female connector elements mating when brought into surface-to-surface contact and interlocking with one another on relative movement of one of said elements relative to the other one thereof.

10 3. A connector device as defined in claim 2, wherein said groove formed in said female connector element is provided with an undercut at each side of said recess to receive said dovetailed key therein.

15 4. A connector device as defined in claim 3, wherein said flange on said male connector element is arcuate in configuration and terminates in said one arm of said male connector element and at the outer terminal end of said male connector element, and wherein said groove formed in said female connector element opens into said one arm thereof and into the terminal end at its other respective end.

20 5. A connector device as defined in claim 4, wherein each of said male and female connector elements is provided with bight portions adapted to receive and sustain a load thereover.
